GEORGE W. WALKER, OF LOWELL, MASSACHUSETTS.

Letters Patent No. 90,974, dated June 8, 1869.

IMPROVEMENT IN SHOULDER-BRACES.

The Schedule referred to in these Letters Patent and making part of the same.

To all whom it may concern:

Be it known that I, GEORGE W. WALKER, of Lowell, in the county of Middlesex, and State of Massachusetts, have invented a certain new and useful Improvement in Shoulder-Braces, of which the following is a full, clear, and exact description, reference being had to the accompanying drawings, making part of this specification, in which—

Figures 1 and 2 represent each my improvements, as applied to the body of a person; the former as connected to a body-belt, and the latter to the rear buttons of the pantaloons of the wearer.

This invention consists in the application of a triangular-shaped gusset, A, of elastic, or flexible, or other fabric, united to the lower edge of the shoulder-strap B, and to the outer edge of the back-strap C of a shoulder-brace, as clearly shown in the drawings.

The object of this invention is to sustain the shoulder-straps and the back-straps, and hold them in position, to prevent them being drawn out of shape by any motion of the wearer; to prevent any undue movement of the back, or shoulder-straps, which will change their particular shape, or angles of connection; and to assist in keeping the straps B on the points of the shoulders, without obstructing the free use of the arms.

This combination of the gussets, the back-strap, and the shoulder-straps, perfectly secures the position of the brace to, or upon the points of the shoulders, where it belongs.

All other attempts with straps, or concaves, have either proved a failure, or hindered the free use of the arms and the shoulders.

This combination provides a ready remedy for the above-named difficulties, and is free from such objections.

The gusset being united to a considerable portion of the length of the lower edge of the shoulder-strap, and the outer edge of the back-strap, prevents any change in the shape, or the peculiar angles of connection caused by the action of the elastic, or other cross-strap D; and this result, or effect cannot be accomplished by a strap of any kind, as the strap is only capable of connection at the two ends, and such a device allows the cross-strap D to draw and change the angles, and misshape the brace, greatly to the inconvenience and discomfort of the wearer, besides injuring the brace.

This invention is intended as an improvement on my former invention and patent, of January 31st, 1865; and I find it admirably adapted to various other kinds of shoulder-braces, but more particularly to such as are shown in the drawings, and having vertical or parallel back-straps, and oblique shoulder-straps connected with the former, and leading to, and over the points of the shoulders, as shown, and here the gusset is of considerable importance for the purposes and objects described.

In this application, I disclaim the use of an auxiliary brace-strap, extending from the strap B to the lower part, or end of the back-strap, for such a strap will not produce the result, or effect described; but

I do claim, the combination, with the shoulder-strap B, and the back-strap C, of the gusset A, as shown and described, when arranged and applied in the manner and for the purpose specified.

GEO. W. WALKER.
